Primary Examiner — Ryan Harvey**CLAIM**

The ornamental design for a walking treadmill, as shown and described.

DESCRIPTION

FIG. 1 is a front, top perspective view of a walking treadmill, showing our new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is an enlarged view of detail “9” identified in FIG. 2. The dashed lines in the figures illustrate portions of the walking treadmill that form no part of the claimed design. The dash dot dash lines in FIGS. 2 and 9 are for the purpose of illustrating the enlarged view indicators and form no part of the claimed design.
